UNITED STATES PATENT OFFICE

WALTER M. ROWLES, OF ONAWA, IOWA, ASSIGNOR TO ECONOMY HOUSING CO., INC.,
OF ONAWA, IOWA, A CORPORATION OF IOWA

DESIGN FOR A TOURIST HOUSE

Application filed May 21, 1930. Serial No. 35,707. Term of patent 14 years.

To all whom it may concern:

Be it known that I, WALTER M. ROWLES, a citizen of the United States, and a resident of Onawa, in the county of Monona and State of Iowa, have invented a certain new, original, and ornamental Design for a Tourist House, of which the following is a specification, reference being had to the accompanying drawings, forming part thereof.

I claim:

The ornamental design for a tourist house as shown.

Des Moines, Iowa, April 2, 1930.
WALTER M. ROWLES.
